CATHODE STRUCTURE

Harry T. O'Neill, Taunton, Mass., assignor to the
United States of America as represented by the
Secretary of War

Application February 18, 1946, Serial No. 648,544

2 Claims. (Cl. 250—27.5)

1

This invention relates to electronic devices, and, more particularly to an electronic vacuum tube of the resnatron type for generating ultra-high frequency power.

Because of the high power output of the resnatron type tube, and the high temperatures developed within the device and between the electrodes thereof, fluid cooling means are customarily associated with the device, particularly with the cathode unit, with the screen or accelerating grid, and with the anode. It is common practice to incorporate a flexible, generally cylindrical, bellows in the cooling arrangement for the cathode unit, the bellows being of a metallic material, and soldered at a lower open end portion to a suitable conforming-shaped portion of the cathode unit, for example, an upper ring-like metallic portion thereof on which one end of the cathode filaments are terminated. Failure of the soldered seal between the bellows and the cathode unit results in the destruction of the vacuum within the tube through leakage of the cooling fluid. During the operation of the resnatron, a large amount of heat must be carried through the cathode portion to which the bellows is connected, and to the cooling fluid. When a recirculating water system is used for cooling, the water may run hot enough to allow the cathode ring-like upper portion to reach the melting point of the solder in the region where the bellows is attached, thus loosening it and filling the vacuum system of the tube with water.

An object of the invention is to improve the structure of a resnatron to minimize the possibility of failure of the vacuum therein because of leakage of cooling fluid.

A feature of the invention comprises securing the referred-to bellows to the cathode unit of a resnatron, with a clearance space provided between a portion of the bellows and the cathode unit to increase the heat radiating area of the cathode unit.

A more complete understanding of the invention will be obtained from the detailed description that follows, taken in conjunction with the showings of the appended drawing, wherein:

Fig. 1 shows a cross-sectional view of the cathode unit of a resnatron incorporating this invention; and

Fig. 2 is a sectional view of the device of Fig. 1 taken along the line 2—2 thereof.

With reference to the drawing, there is shown a cathode unit 10 of a resnatron, including a cathode comprising a plurality of cathode filament wires 12, spaced from each other but ar-

5 ranged to form a generally cylindrical, cage-like structure having a pair of metallic members or rings 14, 16 at their upper and lower ends to which the ends of the individual wires 12 may be soldered. The members 14, 16 have central passages 18, 20, respectively, for suitable conduits or pipes (not shown) for cooling fluid, for example, water, as already well known in the art. A generally cylindrical, flexible bellows or sylphon 22 that 10 may form a part of the cooling means for the resnatron has a lower portion 24 that extends into the passage 18 and is fastened to the passage-way wall, for example, with solder. The upper portion 26 of the ring 14 is recessed or cut away 15 to provide an annular recess or space 28 between the bellows portion 24 and the ring 14. The provision of the recess 28 adds the heat radiating surface of the unit. The cooling fluid that flows 20 inside the ring and the bellows reduces the temperature of the solder seal which the bellows forms with the ring 14. The possibility that the vacuum of the resnatron tube will be disturbed as 25 a result of leakage of cooling fluid through the upper cathode ring—bellows seal is markedly minimized.

Although the invention has been disclosed with reference to a specific configuration, obviously it is not limited thereto, but is to be considered of a scope within the purview of the prior art 30 and the appended claims.

What is claimed is:

1. An electronic device comprising a cathode unit including a plurality of filament wires spaced from one another and mounted in a generally cylindrical configuration, vertically spaced centrally-apertured metallic cooling members to 35 which the upper and lower ends of said wires are respectively secured and a bellows having an end portion extending into the central aperture of one of the upper said metallic members and secured to the aperture thereof, said last-mentioned metallic member providing an annular space surrounding said end portion, said bellows being open to receive circulating water passing through the central apertures of said metallic members.

2. An electronic device comprising a cathode unit including a plurality of filament wires, a centrally-apertured metallic member providing a support for the upper end of said filament wires, and a bellows forming a portion of a cooling system for the cathode unit, said bellows having an end portion extending into the aperture of said metallic member and secured thereto, said member being countersunk around said end portion to provide an annular space therearound,

said bellow being open to receive circulating water passing through the central apertures of said metallic members.

Certificate of Correction

Patent No. 2,452,786

November 2, 1948

HARRY T. O'NEILL

It is hereby certified that errors appear in the printed specification of the above numbered patent requiring correction as follows:

Column 2, line 38, for the words "having and" read *having an*; line 40, strike out "the upper" and insert the same after "aperture of" in line 39; line 49, for "end" read *ends*;

and that the said Letters Patent should be read with these corrections therein that the same may conform to the record of the case in the Patent Office.

Signed and sealed this 17th day of January, A. D. 1950.
